John Wesley Anderson and Lewis H. Kinsley, Jr.,
Philadelphia, Pa.

Application May 11, 1951, Serial No. 15,142

Term of patent 14 years

(Cl. D2—3)

To all whom it may concern:

Be it known that we, John Wesley Anderson and Lewis H. Kinsley, Jr., both citizens of the United States, residing at Philadelphia in the county of Philadelphia and State of Pennsylvania, have invented a new, original, and ornamental Design for a Container Capper, of which the following is a specification, reference being had to the accompanying drawing, forming part hereof.

Fig. 1 is a perspective view of a container capper embodying our new design; Fig. 2 is a front elevational view of the container capper shown in Fig. 1; Fig. 3 is a side elevational view of the container capper shown in Fig. 1; and Fig. 4 is a top plan view of the container capper taken along line 4—4 of Fig. 3.

We claim:

The ornamental design for a container capper, as shown.

JOHN WESLEY ANDERSON.
LEWIS H. KINSLEY, JR.
